CONTROL MECHANISM FOR THE OPENING
AND CLOSING OF CONTAINERSHenri Chabbert, Pau, Basses-Pyrénées, France,
assignor to Kenneth T. Caplinger, Seattle,
Wash.Application October 13, 1945, Serial No. 622,165
In France December 22, 1944

4 Claims. (Cl. 206—56)

1

The present invention is concerned with containers and more particularly with lipstick holders. This invention has more specially for its object a control mechanism for the means securing the opening and closing of the holder's aperture by which the lipstick can protrude.

The mechanism according to this invention comprises, substantially, the combination of an external handling piece protruding from one end of the holder, of at least one hemispheric cap located at the other end of the holder, of a control organ actuated by the rotation of the handling piece and adapted to be longitudinally displaced with respect to the holder, and of connecting means adapted to connect the control organ to the hemispheric cap or caps.

The external handling piece advantageously constitutes the bottom of the holder, and is permanently connected to the latter so as to rotate with respect to said holder, round their common axis.

The handling piece actuates the control organ through a pin compelled to be displaced in a slope of said control organ. Means are provided to secure a longitudinal displacement of said organ with respect to the holder but to prevent any rotation with respect to the same.

The pin which is displaced in a slope of the control organ is simultaneously compelled to be displaced in a second slope and in a longitudinal slot respectively provided in two tubes coaxial with the control organ, said second displacement securing the up-stroke of the lipstick.

According to a characteristic of this invention, the control organ is connected to the closing means through a rigid piece, e. g. a metallic rod.

It is understood that the closing means may comprise a unitary cap member which, in being operated from the open to the closed position or vice versa, undergoes a movement of relatively high amplitude. It may also consist of two conjugated members of smaller dimension, each of which, in swinging to the desired position of adjustment, undergoes movement of smaller amplitude. In the latter instance, a connecting rod joins each of the members with the control organ.

According to another characteristic of the present invention, the two connecting rods are elastically urged one towards the other. By way of example, said rods are made from a single metallic rod suitably bent, so that the inherent elasticity of the rod urges their free ends in the direction towards engagement one with the other.

The mechanism is set up so that the articulations of the rods on the caps are above the point

2

where the caps are pivoted together when said caps are in the position of closing and below said point when the caps are in the position of opening. The elasticity of the rods acts to maintain the caps in the position where they were brought.

Other characteristics of this invention will result from the following description of one embodiment thereof, with reference to the annexed drawing in which:

10 Figure 1 is an elevational view of the lipstick holder in closed position with parts diagrammatically illustrated and some in section more clearly to illustrate the invention;

15 Figure 2 is an elevational view of the lipstick holder with the cap intermediate of the open and closed position; and

Figure 3 is an elevational view of the lipstick holder in open position.

In the drawing is illustrated a lipstick holder. 20 As it is known, said holder comprises a body 1, a central tube 2 slotted at 3, another tube 4 coaxial with tube 2 and in which is provided an helicoidal slope 5, a handling knob 6 disposed at the lower end of the holder and rigidly connected with the tube 2, e. g. by a rivet or the like. The lipstick proper 8 is mounted in a thimble (not shown) fitted with a radial finger 9 which extends through the helicoidal slope 5 and the slot 3. These elements are already known and it is also known that, by a mere rotation of the handling knob 6, the lipstick proper 8 is lifted or lowered, the finger 9 cooperating with both the slot 3 and the slope 5.

According to the invention, a cylindrical sleeve 35 10 is provided coaxially with the tubes 2 and 4. A finger 11 rigidly connected with the tube 4 which is immovable with respect to the body or outside casing 1 as effected, for example, by means of a joining cup-shaped member 4a, penetrates in a slot, not shown, of the sleeve 10. In this sleeve 10 is cut an helicoidal slope 12 in which the finger 9 is also compelled to move.

The slope 5 comprises a first descending part 45 13 and an ascending part 14, and the slope 12 is all ascendant. Two rigid rods 15—16 are linked at 17 on the sleeve 10, and each of which is linked, at its opposed end on a shutter such as 18, 19 which are pivotally mounted together on the cup-shaped member 4a, and having by example the shape of a spherical cap.

The rods 15—16 are made from a length of steel wire conveniently bent and the points 21—22, at which they are linked to the caps, are located above the articulation 20 of the caps, in the position of closing (Fig. 1), and under said point

20 in the opening position (Fig. 3). When they are free, the opposed ends of the rods 15-16 are in contact.

The mechanism above described works as follows:

When the handling knob 6, which is supposed to be in the position shown on Fig. 1, is rotated, the finger 9 is first compelled to go down along the portion 13 of the slope 5. The sleeve 10 is so urged downwards at a great speed through the pressure exerted by the finger 9 on the lower part of the slope 12. The lipstick proper has not yet initiated its upward movement which will only begin when the finger 9 will be in the portion 14 of the slope 5. At this moment, the sleeve 10, refrained from being rotated, by reason of the finger 11, has been downwardly displaced. Through the action of the rods 15-16, the two spherical caps 18 and 19 have been compelled to swing round their common hinge 20, as shown in Fig. 2, liberating the aperture 24 of the holder. If the knob 6 is kept on rotating in the same direction, the sleeve 10 is led to its maximum downward position, which results in the complete opening of the two caps, while the finger 9 keeps on ascending involving the coming out of the lipstick 8 (Fig. 3).

The rotation of the handling knob 6 in the reverse sense, brings on the downward displacement of the lipstick 8, the finger 9 being displaced along the slope 5 only; then, the rotation being prolonged, said finger gets into contact with the upper edge of the slope 12, which induces the upward displacement of the sleeve 10, so that the two caps begin to close the aperture 24 while the lipstick is ending its downward movement in the holder. If the knob 6 is kept on rotating, the finger 9 enters the portion 13 of the slope 5 and the sleeve 10 is brought to its upper position; the lipstick remains motionless and the caps 18-19 are joined together again. The mechanism is returned in the position shown in Fig. 1.

By reason of the elastic pressure exerted on the caps by the rods 15-16, the holder can only be closed or open, but never half-closed.

What I claim is:

1. Opening and closing mechanism for a container, more specifically for a lipstick holder carrying the lipstick on a thimble, which comprises, in combination, an external handling piece protruding from one end of the holder, two arcuate caps pivotally mounted at the other end of the holder for swinging movement between positions opening and closing the end of the holder, a control organ mounted for guided longitudinal movement with respect to the holder and having an inclined slot therein, a longitudinally slotted tube rigid with said handling piece, another concentric tubular member rigid with said holder and having a slot with a first downturned portion and then a helical upturned portion, a pin rigid with said thimble and cooperatively engaging each of said slots whereby turning movement of said handling piece effects longitudinal movements of said pin and said control member, and rigid rods positively connecting said control organ with said closing caps.

2. Opening and closing mechanism as claimed

in claim 1, in which the rigid rods connecting said control organ with said closing caps are constantly urged in the direction towards engagement one with the other.

3. Opening and closing mechanism for a container, more specifically for a lipstick holder carrying the lipstick on a thimble, which comprises, in combination, an external handling piece protruding from one end of the holder, two arcuate caps pivotally mounted at the other end of the holder for swinging movement between positions opening and closing the end of the holder, a control organ mounted for guided longitudinal movement with respect to the holder and having an inclined slot therein, a longitudinally slotted tube rigid with said handling piece, another concentric tubular member rigid with said holder and having a slot with a first downturned portion and then a helical upturned portion, a pin rigid with said thimble and cooperatively engaging each of said slots whereby turning movement of said handling piece effects longitudinal movements of said pin and said control member, and at least one elastic V-shaped member, the base of which is rigid with the control organ and the free ends are respectively linked to each of the closing caps.

4. Opening and closing mechanism for a container, more specifically for a lipstick holder carrying the lipstick on a thimble, which comprises, in combination, an external handling piece protruding from one end of the holder, two arcuate caps pivotally mounted at the other end of the holder for swinging movement between positions opening and closing the end of the holder, a control organ mounted for guided longitudinal movement with respect to the holder and having an inclined slot therein, a longitudinally slotted tube rigid with said handling piece, another concentric tubular member rigid with said holder and having a slot with a first downturned portion and then a helical upturned portion, a pin rigid with said thimble and cooperatively engaging each of said slots whereby turning movement of said handling piece effects longitudinal movements of said pin and said control member, and at least two rigid rods elastically urged one toward the other and operatively connecting said control organ to said closing caps, the articulations of said rods on said closing caps being above the point where the caps are pivoted together when they are in the closed position, and below said pivotal point when they are in the open position.

HENRI CHABBERT.
